11 Claims. (Cl. 171—118)

1

The present invention relates to a new and improved device for closing a switch for the connecting in parallel of two alternating current networks or of alternating current network with an incoming generator. Connection in parallel of alternating current systems with comparatively great differences of frequencies is only possible when the time interval associated with the connecting operation, namely the time constant of the switch is taken into consideration by a certain angle of advance which corresponds to the momentary difference in frequency between the two networks, so that closing of the breaker contacts takes place at zero phase displacement. The different appliances in use up to the present time have many disadvantages, their construction is complicated and they are unreliable in operation.

The object of the invention is to provide a new, simple and reliable arrangement of a device which allows the actual closing of the breaker contacts of the two networks to take place at phase coincidence.

A further object of the invention consists in the provision of an appliance for parallel connection, in which the connection takes place at the correct time when phase coincidence has been established, whereby at the same time, however, the difference in frequency may vary within predetermined adjustable limits. The invention will be better understood from the following description taken in connection with the accompanying drawings in which a device for connecting in parallel two networks is shown in a diagrammatical manner.

In the drawing a contact A is rotatably mounted on the shaft of a synchronoscope, the speed of rotation of which is equal to the difference of frequencies between the two networks, it also indicates the instantaneous relative phase position of the incoming generator. At the same time a second contact B, arranged concentrically with A, moves at a speed that is directly proportional to the difference of frequencies between the two networks. When now contact A in its travel slides over the contact B, electrical contact is established between them, the operation of closing the breaker switch starts, with due regard to the time element and the angle of advance required due to the particular closing time constant of the breaker switch, the actual closing of the breaker contacts occurring at zero phase displacement.

The two networks 1 and 2 can be connected in parallel by means of the breaker switch 3. A

2

synchronoscope 7 is connected with both networks through the two transformers 5 and 6. A pointer arm 24 with a rolling contact A is rigidly connected to the rotatable shaft 28 of the synchronoscope 7. The rolling contact A is in continuous engagement with the larger circumference of a stepped pulley 23 and is adapted to conductively engage a contact B mounted at one point of this circumference. The stepped pulley 23 is freely rotatably mounted on the shaft 28 and its smaller diameter step is engaged by an endless belt 22 passing also over another stepped pulley 14 having one of its steps engaged by a belt 30, the parallel ends of which are secured each by a spring 15 to an anchor bar 16. The belt 30 and the springs 15 yieldingly resist rotation of the pulleys 14 and 23 and try to maintain and return the same to a position in which the contact B on the pulley 23 is in a certain rest position O as indicated by a pointer 25 secured to the pulley 23 and playing over a scale on a stationary dial 26. The stepped pulley 14 is fixedly mounted on a rotatable control shaft 29 of an eddy current coupling as will appear presently.

The shaft 28 has rigidly secured thereto a gear 8 which meshes with a gear 8a fixed to the rotor shaft 31 of an electro-magnetic eddy current slip coupling. This electromagnetic slip coupling consists essentially of a rotor 9 having solid poles and a cylindrical stator 10 provided with an annular exciting coil 32. The rotor 9 is driven by means of the gears 8 and 8a from the shaft 28 of the synchronoscope 7. The coil 32 is energized with direct current by the lines 13 containing a regulating resistance 12. An aluminum drum 11 which is fixedly secured with one of its ends to the previously mentioned rotatable control shaft 29 extends freely movable into the air gap formed between the stator bore and the rotor 9. The aluminum drum 11 serves as an inductor in which are produced eddy currents when the exciting coil 32 is energized and the rotor 9 is rotated by the shaft 28 and the gears 8 and 8a. The eddy currents for a predetermined excitation are proportional to the number of revolutions of the rotor 9 and the shaft 28 respectively, and are also proportional to the counter torque acting on the aluminum drum 11, and derived from the belt and spring assembly 30, 15 which, as mentioned previously, resists yieldingly any rotative movement of the stepped pulley 14 fixedly secured to the shaft 29.

The degree of angular displacement of the drum 11 and of the contact B from its normal

zero position for a predetermined excitation of the coil 32 is therefore a function of the speed or number of revolutions of the shaft 28 of the synchronoscope, or in other words, it is a function of the difference in frequency between the two networks.

A third step of the stepped pulley 14 is provided with a contact sector 17 of a frequency limit control device. Two contact rollers 19 are in continuous rolling contact with the circumference of the third step of the stepped pulley and in certain positions of the latter are both in conductive contact with the contact sector 17. The rollers 19 are adjustable along stationary conductor rails 18 arranged concentrically about the pulley 14 and are provided with pointers 20 indicating the adjusted position of the rollers 19 on a stationary dial 21. The contact B is conductively connected by a lead 35 with the relay 4 which when energized will actuate the breaker switch 3 and thereby the two networks 1 and 2 will be connected with each other in parallel. The contact roller A is conductively connected by the pointer arm 24, a sliding contact brush 36 and a conductor 37 with one of the two conductor rails 18. The other conductor rail 18 is connected with the relay by a conductor 38.

From the above described circuit connections it is obvious, that the relay 4 can only be operated to close the breaker switch 3 when firstly, the contact roller A engages the contact B, and secondly, when at the same time the contact sector 17 is engaged by both rollers 19.

The adjustable resistance 12 is employed for changing the excitation of the coil 32 so that the angle of advance can be adjusted to correspond to the time constant of the breaker switch 3 so that the latter is automatically closed at the very moment the phases of both networks 1 and 2 are coincident with each other.

The mode of operation is as follows:

If the prevailing difference of frequencies between the two networks is greater than that predetermined by the adjustment of the rollers 19 along with their respective rails 18, the torque exerted by the drum 11 will be sufficiently great to cause the sector 17 to rotate out of engagement with one of the contact rollers 19. The relay controlling circuit is interrupted and closing of the breaker contacts cannot take place. As soon as the frequency difference becomes smaller and comes within the predetermined permissible limits, both rollers 19 will engage the sector 17. Connection can then be established to close the breaker contacts when contact B comes into contact with A during its rotary motion.

The angular deviation of the pointer 25 on the pulley 23 from the zero position on the dial 26 indicates the momentarily prevailing frequency difference. This deviation corresponds directly to the angle of advance and the time factor. The angular deviation of the pointer 24 carrying the contact A from the pointer 25, however, indicates the momentarily prevailing difference in the phase position between the two networks.

This arrangement can be improved by duly taking into consideration the momentary difference of acceleration of frequency of the two nets. This can be accomplished by adjusting the anchor bar 16 of the springs 15, the bar is moved horizontally either to the right or to the left, depending on the sign of the acceleration-difference.

The electric synchronoscope can also be re-

placed by two synchronous motors and a mechanical differential gear.

What it is desired to secure by United States Letters Patent is:

- 5 1. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said shaft and including a control device arranged in said electric circuit means for preventing the closing of said electric switch as long as the difference in frequency between the two networks exceeds a predetermined value.
- 10 2. In a device for closing an electric switch for connecting two alternating current networks in parallel, a synchronoscope having a shaft rotating with a speed corresponding to the difference in frequency between the two networks, an electric contact radially spaced from said shaft and carried by an arm fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 15 3. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 20 4. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said shaft and including a control device arranged in said electric circuit means for preventing the closing of said electric switch as long as the difference in frequency between the two networks exceeds a predetermined value.
- 25 5. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 30 6. In a device for closing an electric switch for connecting two alternating current networks in parallel, a shaft rotating with a speed corresponding to the difference in frequency between the two networks, an electric contact radially spaced from said shaft and carried by an arm fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 35 7. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 40 8. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 45 9. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 50 10. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 55 11. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 60 12. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 65 13. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 70 14. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means being actuated by said synchronoscope and including a control device arranged in said electric circuit means for preventing the closing of said electric switch as long as the difference in frequency between the two networks exceeds a predetermined value.
- 75 15. In a device for closing an electric switch for

connecting two alternating current networks in parallel, a shaft rotating with a speed corresponding to the difference in frequency between the two networks, an electric contact radially spaced from said shaft and carried by an arm fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means comprising an electromagnetic slip clutch provided with a pole shoe carrying rotor, a gear connection between said shaft and said rotor, a stator provided with a variable excitable field coil, a cylindrical metallic drum loosely rotatable in the air gap between said rotor and said stator, means for transmitting the rotative movement of said drum to said second electric contact, and a control device arranged in said electric circuit means for preventing the closing of said electric switch as long as the difference in frequency between the two networks exceeds a predetermined value.

5. In a device for closing an electric switch for connecting two alternating current networks in parallel, a shaft rotating with a speed corresponding to the difference in frequency between the two networks, an electric contact radially spaced from said shaft and carried by a member fixedly secured to said shaft, a second electric contact arranged in the path of movement of the first mentioned contact, electric circuit means connected with said two contacts and adapted to cause said electric switch to close when said two contacts engage each other, and means for adjusting said second electric contact concentrically about the axis of said shaft in accordance with the frequency difference between said two networks, said means comprising an electromagnetic slip clutch provided with a pole shoe carrying rotor, a gear connection between said shaft and said rotor, a stator provided with a variable excitable field coil, a cylindrical metallic drum loosely rotatable in the air gap between said rotor and said stator, spring actuated means for resisting the rotative movement of said drum, means for transmitting the rotative movement of said drum in excess of that compensated by said spring actuated means to said second electric contact, and a control device arranged in said electric circuit means for preventing the closing of said electric switch as long as the difference in frequency between the two networks exceeds a predetermined value.

6. A device as claimed in claim 4, including a pointer connected with said second contact and a stationary dial having a scale associated with said pointer to indicate the momentary difference in frequency between the two networks.

7. A device as claimed in claim 4, including a pointer connected with said second contact, a stationary dial having a scale associated with said pointer to indicate the momentary difference in frequency between the two networks, and another pointer connected with said contact carried by the arm on said shaft, the angular distance between said two pointers indicating the momentary angular phase displacement between the two networks to be connected in parallel.

8. A device as claimed in claim 5, including a control shaft on which said drum is fixedly se-

cured, a multi-step pulley secured to said control shaft, another pulley on said first named shaft which rotates with a speed corresponding to the difference in frequency between the two networks, 5 an endless belt connecting the last named pulley with one step of the multi-step pulley on the control shaft, a belt passing over another step of the multi-step pulley, the ends of said belt being arranged substantially parallel, and springs attached to the parallel ends of said belt and to an anchor bar, so as to retain the belt tensioned and resisting rotative movement of said pulleys, said contact device being operated by said control shaft which carries a contact element adapted to engage two contacts and close said electric circuit means when the difference in frequency between the two networks is within predetermined limits.

9. A device as claimed in claim 5, including 20 a control shaft on which said drum is fixedly secured, a multi-step pulley secured to said control shaft, another pulley on said first named shaft which rotates with a speed corresponding to the difference in frequency between the two networks, 25 an endless belt connecting the last named pulley with one step of the multi-step pulley on the control shaft, a belt passing over another step of the multi-step pulley, the ends of said belt being arranged substantially parallel, and springs attached to the parallel ends of said belt and to an anchor bar, so as to retain the belt tensioned and resisting rotative movement of said pulleys, said contact device comprising a contact sector fixedly attached concentrically on 30 said rotatable control shaft, two stationary contact rails arranged concentrically with respect to said contact sector and carrying each an adjustable contact member adapted to engage said contact sector, the adjustment of said contact members along their respective contact rails determining the limits of the difference in frequency between the two networks within which the electric switch is actuated when both said contact members are engaged by said contact 35 sector.

10. A device as claimed in claim 5, including 40 a control shaft on which said drum is fixedly secured, a multi-step pulley secured to said control shaft, another pulley on said first named shaft which rotates with a speed corresponding to the difference in frequency between the two networks, 45 an endless belt connecting the last named pulley with one step of the multi-step pulley on the control shaft, a belt passing over another step of the multi-step pulley, the ends of said belt being arranged substantially parallel, and springs attached with one end to the parallel ends of said belt and with their other ends to an anchor bar, so as to retain the belt tensioned and resisting rotative movement of said pulleys, said contact device comprising a contact sector fixedly attached to the circumference of another step of said multi-step pulley, two stationary contact rails arranged concentrically with respect to said contact sector and carrying each an adjustable contact member adapted to engage said contact sector, the adjustment of said contact members along their respective contact rails determining the limits of the difference in frequency between the two networks within which the electric switch is actuated when both said contact members are engaged by said contact sector, and a pointer on each said contact members and co-operating with a scale on a fixed dial for indicating the adjustment of said contact members. 50 55 60 65 70 75

11. A device as claimed in claim 5, including a control shaft on which said drum is fixedly secured, a multi-step pulley secured to said control shaft, another pulley on said first named shaft which rotates with a speed corresponding to the difference in frequency between the two networks, an endless belt connecting the last named pulley with one step of said multi-step pulley on the control shaft, a belt passing over another step of the multi-step pulley, the ends of said belt being arranged substantially parallel, and springs attached to the parallel ends of said belt and to an anchor bar, so as to retain the belt

tensioned and resisting rotative movement of said pulleys, said anchor bar being adjustable in a plane parallel to a plane in which said control shaft is arranged to vary the angular zone 5 of the pulley engaged by said belt, said contact device being operated by said control shaft which carries a contact element adapted to engage two contacts and close said electric circuit means when the difference in frequency between the two networks is within predetermined limits.
